(57) **CLAIM**

The ornamental design for a vegetation container, as shown and described.

DESCRIPTION

FIG. 1 is a perspective view of a vegetation container showing our new design;

FIG. 2 is a top view of the vegetation container;

FIG. 3 is a front view of the vegetation container;

FIG. 4 is a cross-section front view of the vegetation container taken along the lines 4-4 of FIG. 2;

FIG. 5 is a side view of the vegetation container;

FIG. 6 is a cross-section side view of the vegetation container taken along the lines 6-6 of FIG. 2; and,

FIG. 7 is a bottom view of the vegetation container.

1 Claim, 7 Drawing Sheets
